Patented Dec. 5, 1967

209,466

PAYROLL COMPUTER FACEPLATE

Walter Schaffer, 202—19 45th Drive,
Bayside, N.Y. 11361

Filed Jan. 26, 1967, Ser. No. 5,574

Term of patent 14 years

(Cl. D52—6)

The drawing is a perspective view of the payroll computer faceplate.

The bottom of the faceplate is plain in appearance.

The essential features of the design reside in the solid line portions.

I claim:

The ornamental design for a payroll computer faceplate, substantially as shown and described.
